UNITED STATES PATENT OFFICE

CURT HILSCHER AND ANTON LOIMANN, OF CHEMNITZ, GERMANY

KNOCK-OVER BIT APPARATUS

Application filed December 19, 1930, Serial No. 503,404, and in Germany August 16, 1930.

This invention relates to a knock-over bit apparatus for taking the meshes off the needles in cotton machines. The apparatus includes sets of long and short knock-over bits 5 divided into groups for the purpose of automatically, when desired, bringing certain portions of the fabric beneath the short bits and thus out of working position, while other portions of the fabric are retained in working position above the long bits. An apparatus of this type is shown in U. S. Patent 10 No. 1,876,417, September 6, 1932.

In the operation of a knock-over bit apparatus of this sort, the downward movement of the needles will carry the fabric against the upper surface of the long bits, while at the same time the row of needles may be so positioned that the portions of fabric opposite short bits will be carried 20 down and brought beneath the latter.

In the earlier forms of construction, no provision was made for bringing the fabric which had been brought below the bits back again into its upper working position, and 25 this had generally to be done by hand. In the apparatus of the present invention means are provided for retaining these parts of the fabric close beneath the short bits in order that they may readily be brought above the 30 bits, simply by certain automatic motions of the needles.

To this end the short knock-over bits are provided with protruding beaks placed so as to form a slit between the beaks and the 35 bottom of the bits. Portions of the fabric may thus be brought below the bits and retained in the slit until it is desired to work these portions again. The fabric may then be 40 moved out of the slit and up into working position automatically by a relatively slight upward movement of the needles.

A practical embodiment of the invention is represented in the accompanying drawing, in which 45

Fig. 1 shows the initial position of the mesh-forming parts.

Fig. 2 shows the position of the fabric *e* after being brought downward by the movement of the needles and inserted into the 50 slit *o*.

Fig. 3 shows the first stage of the upward movement, at the moment when the needles have brought the fabric *e* in the direction of the arrow out of the slit *o* beneath the movable knock-over bit *d*. 55

Fig. 4 shows how the needles are able on their upward movement to take the fabric *e* up into working position past the ends of the short knock-over bits. 60

Fig. 5 shows the upward movement of the needles at approximately its final stage, the needles starting to move in the direction of the arrow toward the back of the machine. 65

Fig. 6 shows the needles at their extreme point toward the back of the machine, the fabric *e* now being in position to be worked above the knock-over bits. 70

Fig. 7 represents a modified form of construction in which the beaks are formed by separate projecting members, instead of being made as a part of the short knock-over bits. 75

As shown in the drawing, the short bits *d* are provided with a beak *d*¹ so arranged as to form a slit *o* between the top of the beak and the under side of the bit. 80

In Figs. 3 to 6 is shown a portion *f* of the fabric which is retained continuously in working position and so is worked to form a loop while another portion *e* is held under the bits without being worked. The portions *e* of the fabric which are drawn in heavy lines are those which are periodically brought below and above the bits. Those portions *f* of the fabric which are drawn in light double lines show the parts of the fabric which are worked along while the portion *e* is held at rest. 85

The distance between the needle *a* and the 90

line *g* shows the number of meshes which is necessary (approximately the length of the knock-over bits) to permit separation of the fabric into portions below and above the bits.

- 5 5 The point *g* thus forms the apex-point of the connection between the fabric portions *e* and *f*.

Naturally there will not be on one and the same needle simultaneously the fabric *e* and 10 the fabric or fabric loop *f*, but there will be on the needles in the sections of the short bits the fabric *e* and in the sections of the long bits the fabric *f*.

15 The beaks *d*¹ may be made to form one piece with the short bits *d*, or they can, as shown in Fig. 7, be formed by the separate projecting members *h* which are fixed in the bit support *i* in any suitable manner, so as to form the slit between the short knock-over 20 bits *d* and the members *h*.

The mode of operation may be summarized as follows:

25 On beginning to work the foot portion, it is intended to automatically bring the fabric of the middle part which has been held blocked within the slit out of said slit. This is effected by causing the needles *a* to make a greater movement forward (toward the right in Fig. 4) so that the meshes of the portion *e* may, on 30 the upward movement of the needles, pass by the front edge of the short knock-over bits, and so can be carried upward by the needles over said bits, being thus brought into working position above the bits as clearly shown 35 in Figs. 5 and 6. It will be understood that these parts remain in working position so long as the needles are not moved forward beyond the ends of the short bits.

40 What we claim is:

40 1. A knock-over bit apparatus for taking the meshes off the needles in cotton machines comprising, a group of longer knock-over bits, a group of shorter knock-over bits, the machine needles and bits being relatively 45 movable so as to permit an edge of the fabric to pass the ends of the shorter bits in a vertical direction, and means for preventing those portions of the fabric edge which are brought down past the ends of the shorter 50 bits from following the full downward motion of the needles.

55 2. A knock-over bit apparatus for taking the meshes off the needles in cotton machines comprising, a group of longer knock-over bits, a group of shorter knock-over bits, the machine needles and bits being relatively 60 movable so as to permit an edge of the fabric to pass the ends of the shorter bits in a vertical direction, and projecting members beneath the shorter bits and disposed to form a fabric-receiving slit between said bits and said members.

65 3. A knock-over bit apparatus for taking the meshes off the needles in cotton machines comprising, a group of longer knock-over

bits, a group of shorter knock-over bits, the machine needles and bits being relatively movable so as to permit an edge of the fabric to pass the ends of the shorter bits in a vertical direction, and members projecting beneath and beyond the ends of the shorter bits, and disposed to form a fabric-receiving slit between said bits and said members.

In testimony, that we claim the foregoing as our invention, we have signed our 75 names this 6th day of December 1930.
